DOORKNOB

Adolf Schoepe, Fullerton, Calif., assignor to Kwikset Locks, Inc., Anaheim, Calif., a corporation of California

Application November 10, 1955, Serial No. 38,855

Term of patent 14 years

(Cl. D50—3)

Fig. 1 is a perspective view of a doorknob showing my new design;

Fig. 2 is a front elevation taken from the arrow 2 of Fig. 1;

Fig. 3 is a side elevational view taken from the direction of the arrow 3 of Fig. 1; and

Fig. 4 is a side elevational view taken from the direction of the arrow 4 of Fig. 1.

I claim:

The ornamental design for a doorknob, as shown.
